UNITED STATES PATENT OFFICE

PERLEY R. GLASS, OF WAYLAND, MASSACHUSETTS, ASSIGNEE TO UNITED SHOE MACHINERY CORPORATION, OF PATERSON, NEW JERSEY, A CORPORATION OF NEW JERSEY

STAMPING MACHINE

Application filed December 21, 1927. Serial No. 241,589.

This invention relates to stamping machines and is herein illustrated as embodied in a machine for stamping numbers, names, or the like on shoe soles.

5 In stamping the various desired indicia by impressing a die into the substance of compressible material having a substantial thickness, such as cardboard, leather, and the like, it is essential in order to obtain uniformity in 55
 10 the impressions of the die to take account of the variations in thickness of the pieces of work. Thus in the machine illustrated in United States Letters Patent No. 1,282,158 granted Oct. 22, 1918 on the application of
 15 H. W. Winter, the arrangement is such that a preliminary adjustment for thickness is obtained by moving the die carrying head into contact with the piece of work by an impulsive, frictionally operated wedge so as automatically to bring the die just into contact with the work regardless of its exact thickness. An impression in the work is then effected by positively actuating a toggle to raise the work support to bring the work forcibly 60
 20 into stamping contact with the dies, to the end that the impression shall always be of the same depth.

An object of the present invention is to provide an improved machine of this type arranged to operate even more effectively, and designed for the more convenient presentation of work by the operator so that the production of the machine will be increased.

To these ends and in accordance with one 65
 25 feature of the invention, the machine is arranged to lock a slidable part, which produces the preliminary measuring movement, so that under all conditions and especially when pressure is applied to cause an operation of the tool, the measuring movement will not be disturbed. In the illustrated machine, this locking means takes the form of co-acting surfaces upon the slidable part and the frame of the machine, so arranged that the application of pressure to cause an operation of the tool is effective to lock the slidable part, and, hence, the operating member with which it is associated.

Since it may be assumed that the work to 70
 30 be stamped upon the machine will usually be

of compressible material, it follows that successive lots of work will be found to vary in the quality of the stock. Variation in the thickness of the pieces in successive lots will also be found. Although the illustrated machine, by virtue of the preliminary measuring movement referred to, is arranged for automatic compensation for thickness, it is not desirable to put the whole burden of this work through the whole range of variation 55
 35 upon the automatic mechanism of the machine, and another feature of the invention resides in improved means for adjusting the initial position of one of the members, such as the work support. Still other means are 60
 40 provided for adjustably controlling the depth of impression produced by the machine.

The production of a machine of this class depends very largely upon the facility with 70
 45 which the successive pieces of work may be presented to the machine, and when shoe soles are to be stamped, it is customary for the operator to hold a bunch of soles in this hand spread out in fan-like fashion, these soles being presented successively to the machine 75
 50 by a dexterous twist of the wrist. In the illustrated form of the invention improved means are provided for facilitating the presentation of pieces of work between the stamping die and the work table, in preventing the 80
 55 scarring of the work by accidental contact with the stamping dies, and in automatically stripping the work from the dies after the 65
 60 impression has been made.

In the drawings,

Fig. 1 is a perspective view of a machine, embodying the present invention in a preferred form;

Fig. 2 is a perspective view of a portion of 90
 65 a shoe sole showing the character of work which may be performed by the machine;

Fig. 3 is a longitudinal, vertical section through substantially the center of the machine with some parts shown in elevation;

Fig. 4 is a vertical section through the type carrying head from front to back;

Fig. 5 is a transverse section on the line V—V of Fig. 4 through the auxiliary type carrier; and

Fig. 6 is a section on the line VI—VI of Fig. 3.

The operating parts of the illustrated stamping machine are mounted within a hollow frame 10, having an overhanging portion 12 to provide a recess 14 to allow the introduction of work pieces. As in the machine disclosed in the Letters Patent referred to above, a stamping head 16 is supported for vertical reciprocation in the overhanging portion 12 of the frame, and a work supporting table 18 is mounted for up and down movement in a line with and directly beneath said stamping head 16.

15 The stamping head 16 is detachably secured to the lower end of a forked plunger 20 mounted for vertical reciprocation between the outer face of the overhanging portion 12 and a front cap 22. The plunger 20 is arranged to be moved up and down by means of a wedge or cam member 24, slidably mounted between an upper face of said portion 12 and a detachable top cap 26. This wedge member 24 has an inclined slot 28 which receives a rectangular block 30 pivotally attached by a pin 31 to the forked upper end of the plunger 20, and, as a consequence, movement of the wedge member in one direction causes the stamping head 16 to descend, this descent of the head being positively effected as will be hereinafter explained, and movement of the wedge member in the other direction, positively raises the plunger and stamping head to facilitate the introduction of work beneath the head. Co-acting locking surfaces upon the slidable part and the frame are provided by a beveled upper edge 25 on the wedge member 24 and this edge is received in and coacts with a correspondingly shaped groove 27 in the top cap 26, and normally slides along said groove as the wedge member moves the die carrying plunger 20 up and down. It will be seen that in any of its positions, the stamping head is positively locked against displacement by the application of pressure from beneath both by reason of the angle of the wedge slot 28 with the horizontal and more especially by the wedging of the beveled edge 25 in the groove 27 so as immediately to increase radically the friction between the edge 25 and the groove 27 and consequently to lock the wedge member 24 against displacement.

In the stamping head 16, there is provided 55 a plurality of type carrying wheels 32, each of which is individually held against rotation by means of a latch 34, and may be rotated to change its position when released from the latch, by means of a handle 35 (Fig. 60 1). Reference may be had to United States Letters Patent No. 960,029, granted May 31, 1910 on the application of F. W. Merrick for a more complete disclosure of the type wheels 32 and the operating parts 34 and 35. In addition, the stamping head 16 is extended at

36 to provide for the attachment of an auxiliary die or type carrier 38 pivotally mounted upon a cross rod 40 and latched in operative position by means of a spring pressed plunger having an operating head 42. A 70 spring 44 inserted between the extension 36 of the stamping head 16 and the auxiliary carrier 38 depresses the auxiliary carrier to an extent limited by a stud 46 when the plunger just referred to is retracted by pulling out of the operating head 42. The auxiliary carrier 38 is so arranged that various dies or type pieces may be inserted therein and locked in a groove 48 at one side by an adjustable clamp 50 at the other side. This 80 clamp 50 has a threaded stem 52 for the reception of a clamping screw 54 at the front of the head. It will be observed that the particular die 56 which is illustrated in the drawings is not only provided with dove-tailed slots for the reception of type pieces 58 but also has an edge extension having a printing face 60 and an upper surface 62 which is received in the notch between two adjacent type pieces upon the numbering wheels 90 32. The arrangement is such, therefore, that this extension of the type piece 56 not only interlocks with said numbering wheels, but is supported by the wheels at a point directly over the printing face 60. By this arrangement, the various indicia may be positioned close to one another upon a sole 64 (Fig. 2), thereby to reduce the amount of space occupied by the whole marking 65. The latter may, for example, be made up of a row of 100 numbers, the factory name (ABC), the name of the last (JOHN DOE), and the union stamp.

When an operator inserts a piece of work, such as the sole 64, between the type faces on the stamping head 16 and the work table 18, he will, customarily, fan a small bunch of soles and insert them one after another from the side of the stamping head 16, bringing each one to a position longitudinally of the machine determined by a gage 66 adjustably supported in a boss 68, which is provided in the recess 14 of the frame. This insertion of the work is not only facilitated by the positive raising of the plunger 20 carrying the stamping head thereby insuring the maximum possible space between the head and the table, but also by reason of the provision of a guide 70 having a curved side face 72 and an extension finger 74, the lower face of which is substantially flush with the type pieces 58, etc., so that there is no danger of scarring the work as it is inserted beneath the stamping head. The side face 72 coacts with the table to form a work receiving throat. The guide 70 is carried at the lower end of a rod 76 mounted in lugs 82 on the side of the stamping head and spring pressed to an adjustable operating position by means of a spring 78 surrounding the rod 76, which is 100

arranged normally to hold the guide at the level of the type faces and allows depression of the guide on operation of the machine so that no mark will be made by it upon the work. By reason of this resilient mounting the extension 74 serves as a stripper which prevents any sticking of a sole to the type pieces. This guide 70 is held against rotation by means of a pin 80 entering a slot in the lower lug 82 on the side of the stamping head.

When it is desired to drive the machine by an electric motor 84, such a motor may conveniently be mounted upon a bracket plate 86 which is adjustably secured in position in the frame of the machine by means of a tie rod 88, a detachable cover 90 (Fig. 3) for the motor being provided at the rear of the frame. A bearing member 92 is pivotally mounted upon the bracket plate 86 to receive an Oldham coupling 94, one portion of which is secured to the motor shaft and the other portion of which is secured to a worm 96 which is rotatable about a stud 98 clamped in the bracket 86. This worm engages a worm gear 100 rotatable upon a stub shaft 102 and connected to a pinion 104 which meshes with a gear 106 upon the main shaft 108 of the machine. In the arrangement shown, this gear 106 is loose upon the shaft 108 and is adapted to be connected thereto to drive a cam plate 110 by means of any suitable clutch 112 (Fig. 1) controlled by a treadle rod 114. It will be observed that the cam plate 110 is provided with cam tracks or grooves 116 and 118 controlling the movements of the stamping head 16 and the work carrying table 18.

In order that the wedge member 24 may be impositively operated in one direction to carry the stamping head 16 just into contact with the work, and positively in the other direction to lift the stamping head from the work, the machine is provided with a two-part lever, the lower arm 120 of which is pivotally mounted on a rod 122 and is provided with a roll engaging the cam track 118. The upper arm 124 of this lever is pivoted to the lower part 120 at an intermediate point 125 and is impositively connected thereto by means of a spring 126 surrounding a rod 128 passing through journal blocks pivoted in the upper end of the member 120 and in an intermediate portion of the arm 124. Lock nuts 130 are provided for adjusting the tension of the spring 126 and holding it in adjusted relation. The upper end of the lever arm 124 is connected by a link 132 to the wedge member 24 so that when the cam moves the lever arm 120 to the left in Fig. 3, the wedge member 24 will be impositively moved to the left to bring the type pieces or dies in the stamping head 16 into contact with the piece of work in the machine. Just as soon as they contact with the piece of work, however, the upper and lower arms

124 and 120 of the two-part lever will separate against the tension of the spring 126.

It will be evident that the cam path 118 must be of such a design that the maximum desired throw can be imparted to the lever 120, 124 so that the dies will contact with the surface of the thinnest sole. Consequently, when the dies contact with a sole thicker than this minimum, the action of the wedge member 24 will be resisted and the spring 126 caused to stretch as the lower arm 120 continues to move under the action of the cam path 118, without forcing any further movement of the dies.

When pressure is applied to the work by lifting the work table 18, the wedge member 24 will be securely locked in any position which it may have assumed as the beveled edge 25 is forced into the groove 27 by such pressure. The design of this groove and the beveled edge is such that as soon as the pressure has been relieved, there is little, if any, tendency for the wedge member to stick, and even if there should be any such tendency, it would be promptly overcome by the positive action of the two part lever 120, 124 as the lever is swung to the right, viewing the machine as in Fig. 3, in order to return the wedge member to its original position.

It will be remembered that the connection between the wedge member 24 and the forked plunger 20 which carries the stamping head 16, is such that the return of the wedge member to its original position is effective positively to raise the stamping head 16 to its original position at a point having maximum separation from the work table. Thus, not only the wedge member 24 is moved positively back to its original position but the stamping head 16 is also lifted positively back to its original position, thereby facilitating rapid use of the machine.

The lifting of the work table 18 to cause the stamping head 16 to mark the work is effected by means of a lever 140 pivotally mounted at its lower end on the cross rod 122, and provided at its upper end with a roll engaging the cam track 116. A midway point on this lever 140 is connected to a link 142 joining another link 144, which is connected to a toggle made up of an upper member 146 and a lower member 148. When the lever 140 moves to the left in Fig. 3 it straightens the toggle, carrying it slightly beyond the dead center, to raise the work table 18 and the extent of this movement is determined by varying the position of the pivot 150 between the links 142 and 144. To this end, this pivot 150 is mounted at the upper end of a short arm 152, the lower end of which is mounted upon an eccentric portion 154 (Fig. 3) of a cross rod 156 (Fig. 1), having a handle 158 which may be rotated to various positions and locked in adjusted relation to the frame by engagement of a

spring stud 160 in the handle with one of the holes 162, 163, 164. The arrangement is such that when the adjusting handle 158 is in the illustrated position the pivot 150 will be in its lowest position, thereby lessening the angle between the links 142 and 144 and effectively shortening the connection provided by said links so that the same amount of movement of the lever 140 will be effective to cause a greater displacement of the work table 18 than will be the case when the links 142 and 144 are more nearly in a straight line and, therefore, effectively lengthened, because in the latter condition, the toggle will be nearer straight to start with and the same amount of lateral movement of its intermediate pivot will produce less upward movement of the work table before the toggle passes dead center.

29 Shoe soles not only have small variations in thickness owing to imperfect grading of a single lot of soles, but in different lots may be radically different in thickness, depending, for example, upon whether they are so-called "single" soles or "double" soles. In order to provide an initial adjustment of the work table 18 in accordance with the class of soles being stamped, the machine is provided with another adjusting handle 168 which is similar in construction to the handle 158 and which may be moved from a low position determined by the locking recess 170 to a high position determined by the locking recess 172. The turning of this handle rotates a transverse stud 174 which is provided with an eccentric portion 176 which forms a fixed pivot for the lower toggle member 148. Thus, with the operating link members 142 and 144 in a fixed position, adjustment of the handle 168 lifts the toggle as a whole and, hence, the work table 18 to vary its initial position, thereby to lessen the compensation required of the automatic apparatus in the head of the machine.

45 In the operation of the machine, the type pieces and dies upon the stamping head 16 are adjusted, either by rotation of the handle 36 or by placing new pieces 58 or 60 in the auxiliary carrier 38, and the operator will adjust the handle 168 to set the table 18 at a level in accordance with the class of soles to be treated. He then will insert the fanned soles successively laterally into the recess 14 of the frame with the assistance of the guide 70 and position the ends of the soles against the previously adjusted gage member 66. Depression of the treadle rod 114 closes the clutch and effects a single rotation of the cam 110 to cause the machine to go through its cycle of movement or, if the treadle is held down, the cam 110 will keep on rotating. This will first move the wedge member 24 impositively to the left in Fig. 3 to depress the stamping head 16 into firm contact with the work irrespective of its exact thickness

and will hold said stamping head locked in this position. It will next straighten the toggle 146, 148 to lift the work table 18 to force the work into stamping engagement with the stamping dies in the head 16.

70 During the stamping movement, which in this case is effected by the lifting of the work table, the opposing abutment, formed here by the stamping die, is locked in position by reason of the locking of the wedge member 24, and after the stamping has been completed, the wedge member is moved positively to return it to its original position and the stamping die is lifted positively away from the work. In case the characters 65 are not impressed to the exact depth required for the best quality of work, the operator may adjust the handle 158, either to the left to lessen the depth of the impression, or to the right to increase it. The finger 74 of the guide 70 will act as a stripper to keep the soles from clinging to the die and will thereby facilitate the rapid presentation of successive soles to the machine.

80 Having thus described my invention, what I claim as new and desire to secure by Letters Patent of the United States is:

1. In a stamping machine, a frame, a movable work supporting member, a reciprocable die member, a slidable wedge for producing a preliminary measuring movement of one of said members to bring said member just into contact with opposite surfaces of the work, means for imparting an additional pressure to one of said members to cause an impression of the die, and coacting surfaces upon said slidable wedge and the frame of the machine constructed and arranged radically to increase the friction between said surfaces upon the application of pressure, so as to prevent displacement of the wedge in the direction of its length when operating pressure is applied to cause the die to stamp the work.

105 2. In a stamping machine, a reciprocable stamping die, a reciprocable work support in line therewith, a wedge for imparting a preliminary relative measuring movement to one of said members to bring said members into contact with opposite faces of a piece of work, means for imparting an additional impressing movement to cause the die to stamp the work, and means for locking said wedge against displacement by said impressing movement.

110 3. In a stamping machine, a work support, a stamping die, means impositively connected in one direction to one of said members for producing a preliminary relative measuring movement of approach between said members, means for imparting an additional, impressing movement to one of the members, and means for locking the other member against displacement by said impressing movement.

4. In a stamping machine, a work support, a stamping die, means for producing a preliminary relative measuring movement of approach between said members, said means comprising a slidable member, means for applying an impression producing pressure to the other of said members, and means operated by the pressure applied to produce an impression for automatically locking said sliding member, in any position which it may assume, against displacement.

5. In a stamping machine, a reciprocable stamping die, a reciprocable work support in line therewith, a cam for producing a preliminary relative measuring movement of said stamping die, means for lifting said work support to produce an impression of the die upon the work, and means rendered effective by said pressure to lock said cam against displacement.

6. In a stamping machine, a frame, a work supporting member, a stamping die member, means for producing a preliminary measuring movement of approach between said members, said means comprising a slotted cam slidable in a straight line in the frame of the machine, the slot of which cam is operatively connected to one of said members, means for applying an impression producing pressure to the other of said members, and means for automatically locking said slidable cam, in any position which it may assume, against displacement, by the pressure applied to produce an impression.

7. In a machine of the character described, a frame, a movable work supporting member, a reciprocable tool member, a slidable part for producing a preliminary measuring movement of one of said members, means for imparting an additional pressure to one of said members to cause an operation of the tool, and coacting locking surfaces upon said slidable part and the frame of the machine, constructed and arranged to prevent sliding movement of said member when operating pressure is applied to cause the tool to operate upon the work.

8. In a stamping machine, a frame, a reciprocable stamping die, a work support reciprocable in a line therewith, a slidable wedge member for producing a preliminary measuring movement of the stamping die, said wedge member being provided with a beveled edge portion and said frame being provided with a correspondingly shaped groove for the reception of the beveled portion of said slidable member, and means for applying pressure to said work support to cause the die to make an impression in the work, forcing the beveled portion of the slid- able member into the groove in the frame, and locking said slidable member against displacement.

9. In a stamping machine, a work support, a stamping die, a member for producing a

preliminary relative movement of approach between said support and die to bring the support and die just into contact with opposite faces of a piece of work, and means for moving said member impositively in one direction and positively in the other direction.

10. In a stamping machine, a work support, a stamping die, means for producing a preliminary relative movement of approach between said support and die comprising a wedge member, and means for moving said wedge member impositively in one direction and positively in the other direction.

11. In a stamping machine, a work support, a stamping die, means comprising a wedge member for producing a preliminary relative movement of approach between said support and die upon movement of said wedge member in one direction, said wedge member being constructed and arranged positively to separate said work support and die member upon movement in another direction whereby the maximum possible space between the die and the work support is insured, to facilitate the insertion of work pieces in the machine.

12. In a stamping machine, a frame, a work support, a slidable die-carrying head movable toward and away from said work support, a cam slidable in the frame of said machine, said cam having an inclined slot for the actuation of the die-carrying member, and means for sliding said cam in said frame to move the die positively both toward and away from the work support.

13. In a stamping machine, a frame, a work support, a slidable die carrying head, a wedge member slidable in the frame of said machine, having an inclined closed cam slot to produce relative movement of said work support and said die carrying head to bring them just into contact with the opposite faces of a piece of work, means for impositively sliding said wedge member so that it may stop when the member actuated thereby comes in contact with the work, and means for moving positively the slotted wedge member to separate said work contacting members.

14. In a stamping machine, a frame, a work support, a slidable die-carrying head movable toward and away from said work support, a wedge member slidable in the frame of said machine, said wedge member having an inclined cam slot for the actuation of the die-carrying member, and means for impositively sliding the wedge member to cause a preliminary movement of approach of the die member toward the work support thereby to contact with a piece of work.

15. In a stamping machine, a movable operating member, means for moving said member impositively to effect a preliminary measuring of the thickness of the work, said means comprising a jointed lever having over-

- lapping ends which abut to render the lever rigid for action in one direction, means for swinging said lever, and resilient means normally maintaining the angular relation of the parts of the lever with said ends in abutting relation and constructed and arranged to allow a change in the angular relation of said parts when the operating member contacts with the work.
16. In a stamping machine, an operating member movable into engagement with a piece of work, means for moving said member into engagement with the work to effect a preliminary measurement of the thickness of the work, said means being constructed and arranged to hold said member firmly in opposition to the pressure afforded by another operating member, means for impositively actuating said moving means, said last named means comprising a jointed lever, a spring for holding the parts of said lever in a predetermined angular relation in which they are substantially in alinement, and means for moving said lever through a fixed distance to bring said operating member into contact with the work, and then to displace the relative angular relation of the parts of said lever against the tension of said spring.
17. In a stamping machine, a work supporting member and a stamping member, each movable toward and away from the other, means for impositively moving one of said members toward the other to bring said members into contact with the opposite sides of the work and to hold one of the members rigidly in the position which it has assumed, and adjustable means for moving the other member to effect an impression of determinate depth in the work without substantially affecting the initial position of the work support, said means comprising a toggle, an operating link for straightening said toggle comprising pivotally connected parts, means for positively supporting the pivotal connection of said parts, and means for varying the effective length of said link by varying the position of said supporting means, thereby to straighten or bend the link.
18. In a stamping machine, a die-carrying member, a work supporting member, said parts being mounted for movement toward and away from each other in a straight line, means for impositively moving one of said members to bring it into contact with the face of a piece of work supported on the other member and to hold the member in firm contact with the work, operating means for moving said work supporting member to effect an impression of the die upon the work, said means comprising a toggle, and an eccentric bearing for one end of said toggle constructed and arranged to allow a preliminary adjustment of the position of said work supporting member in accordance with the range of thickness of work pieces.
19. In a stamping machine, a frame, a die-carrying member and a work support each mounted for movement toward and away from the other in a straight line, means for preliminarily adjusting the position of one of said members in accordance with the general range of thickness of the class of work under consideration, means including a resilient member for effecting a preliminary measuring movement of one of said members to bring it into contact with the work without thereby disturbing the adjusted position of the other member, and a positive operating means for then bringing said members together to stamp the work.
20. In a stamping machine, a work support and a die-carrying member, each movable toward and away from the other in a straight line, impositive means for preliminarily bringing said members into contact with the opposite sides of a piece of work, positive operating means for causing a further relative movement of said members to effect a stamping operation, and an eccentric connected to the positive operating means for determining the initial position of the work support.
21. In a stamping machine, a die-carrying member and a work supporting member movable relatively to contact with opposite sides of a piece of work, means for adjusting the position of one of said members in accordance with the thickness of the class of work to be stamped, means for impositively effecting relative movement of said members into contact with the opposite sides of a piece of work, positive means for effecting a further relative movement of said members to stamp the work, and means for adjusting the depth of the impression produced by said last-named means.
22. In a stamping machine, a work support, a die-carrying member in line with said work support, means for impositively positioning said die-carrying member and rigidly holding it in position in engagement with one face of a piece of work positioned upon said work support, a toggle for operating said work support to effect an impression of the die, an eccentric bearing for one end of said toggle, and means for operating said toggle comprising a pair of pivotally connected links, a support for said pivotal connection, and an eccentric for adjusting the position of said support, thereby to determine the depth of the impression produced.
- In testimony whereof I have signed my name to this specification.
- PERLEY R. GLASS.
